UNITED STATES PATENT OFFICE.

THOMAS J. DOWNING AND EUGENE J. DOWNING, OF NEW YORK, N. Y.; DELIA DOWNING, ADMINISTRATRIX OF SAID THOMAS J. DOWNING, DECEASED.

SIGNALING DEVICE FOR AUTOMOBILES.

1,242,896.

Specification of Letters Patent.

Patented Oct. 9, 1917.

Application filed April 12, 1915. Serial No. 20,765.

To all whom it may concern:

Be it known that we, THOMAS J. DOWNING and EUGENE J. DOWNING, citizens of the United States, and residents of New York city, in the county of New York and State of New York, have invented certain new and useful Improvements in Signaling Devices for Automobiles, of which the following is a specification.

10 This invention relates to signaling devices for automobiles, and particularly devices of this character for clearly indicating the intended direction of movement on the part of the driver.

15 One object of the present invention is to provide a signaling device having simple means, certain in operation, which will indicate both at the front and rear of the vehicle simultaneously.

20 Another object is to provide a signal which will be plainly visible both in daylight and at night.

A further object is to provide a signal which will be striking in character.

25 The various further objects and advantages will more fully appear from the detailed description and the features of novelty will be particularly pointed out in the claims.

30 In the drawings illustrating the preferred embodiments of this invention,

Figure 1 is a plan view illustrating diagrammatically an automobile with one form of our invention applied thereto.

35 Fig. 2 is a front elevation of the automobile illustrating the general arrangement of the signal at the front of the automobile.

Fig. 3 is an elevational view corresponding to Fig. 1.

40 Fig. 4 is an elevational detail view partly in section illustrating the signaling devices on an enlarged scale.

Fig. 5 is a section taken along line 5—5, and Fig. 6 is a section taken along line 6—6

45 of Fig. 4.

Fig. 7 is a detail view corresponding to Fig. 4, illustrating the signal as actuated to indicating position.

Our invention contemplates generally to 50 provide a striking signal which is distinctly visible both in the daytime and at night, displayed both at the front and rear of the vehicle simultaneously. To this end, we

provide an index which is normally concealed, but which is moved into view by the 55 driver at any time when he desires to signal. At night, when this movable signal would not be readily visible, means are provided in the same device for securing an 60 illuminated signal.

Referring in detail to the drawings, the signals proper 10 and 11 are mounted in casings at the front and the rear of the vehicle and are adapted to be operated simultaneously to indicate whether the vehicle is 65 to turn to the right or to the left. Thus, if the driver intends to go to the right, both of the signals 10 are projected in the front and at the rear, while if he intends to go to the left, the signals 11 are projected. The signals consist preferably of plates mounted in casings 12 and normally hidden from view 70 thereby. When the chauffeur intends to go to the left, for instance, and operates the signal 11, the signal plate is projected into the 75 position indicated in Fig. 7, in which the upper portion of the plate, having the figure of a hand 13 pointing to the left, painted, enameled or otherwise impressed thereon, is brought into view. When the driver has 80 completed his turn to the left and releases the operating mechanism, the springs 14 withdraw the plate into the casing, thus concealing the signal from view.

To make the signal visible at night as well 85 as in the daytime, the casing is provided with a lamp 15 which, when illuminated, throws its light through a glass 16, which has painted, enameled or otherwise impressed thereon, a figure of a hand 17 similar 90 to the hand 13 of the plate 11 and pointing in the same direction. Normally, the plate 11 when retracted in the casing has a portion 18 which conceals the glass 16 from view. However, when the plate is raised to display the signal 13, the portion 18 slides past the glass 16 and exposes the same through an opening 19 in the plate formed for that purpose. A registering opening 20 is, of course, formed in the casing and thus when 100 the signal slide is raised and the lamp is lighted, the index hand 17 will appear illuminated and will be perfectly visible at night when the index hand 18 is not visible.

The plates are operated by mechanism including push rods 21 abutting and engaging

elongated projections 22 extending downward from the plates 10 and 11 into guide casings 23.

Any suitable form of operating mechanism may be used for actuating the signal. We have illustrated a flexible cord mechanism, shown in Fig. 1, the operating device for which is disposed on the steering post 24, easily accessible to the driver. Thus, 10 a lever 27 mounted on the steering post below the steering wheel may actuate a flexible cord 29 guided through a guide tube 31 and passing over a sheave 32 fixed to a shaft 33. The latter may extend the length of the 15 vehicle and may be journaled in suitable brackets 34 and 35. When the driver desires to operate the signal so as to indicate movement to the right or left, he pushes the lever 27 to the right or to the left and 20 so actuates the corresponding signal.

In the daytime, as previously explained, the signal hand 18, which appears above the casing 12, will be very effective to indicate the direction of the vehicle, but at night, 25 it will be necessary to use the illuminated signal glass 16. We provide, therefore, means whereby the lamp 15 is turned on whenever the signals are operated and provide further means whereby this lighting 30 up will occur only at the will of the operator. Thus, a maximum economy of current is effected, inasmuch as the lamp lights up only when the signal is displayed and may be made to light up only at night and 35 not in the daytime. For this purpose, a pair of switches 49 and 50 (Fig. 1) are provided in any suitable place, preferably at the bottom of the vehicle at each side of the shaft 33. Extending from the shaft be- 40 tween the switches is an arm 51 which engages one or the other of the switches to close an electric circuit to light up lamps corresponding to the actuated signal. In the daytime, when the lights are not used, 45 a plug 52 is removed from a suitable point in the wiring to break the electrical circuit of all the lamps.

It will be seen from the above description that we have provided a signal for automobiles which is very striking and effective both in the daytime and at night and is displayed at the front and rear of the machine simultaneously. Although an electric light is used for the night signal, electric current 55 is not used except when the signal is actually displayed, and in the daytime, it is dispensed with entirely, thus securing a maximum economy in operating.

Various modifications may be resorted to 60 within the spirit of the invention and the scope of the accompanying claims.

Having thus described our invention, we claim as new and desire to secure by Letters Patent:

65 1. A signal device for automobiles com-

prising a casing, having an aperture, a movable signal plate mounted in the casing, a transparent signal plate mounted in registry with the aperture, the latter plate being uncovered when the movable signal plate is operated, a projection on the movable signal plate at the lower edge thereof, a rod mounted in line with said projection adapted to make abutting contact therewith, a horizontal arm pivotally mounted and adapted to carry said abutting rod, and means for operating said arm.

2. A signal device for automobiles comprising a casing, a movable signal plate mounted therein, a projection on said plate at the lower edge thereof, a rod mounted in line with said projection adapted to make abutting contact therewith, a horizontal arm pivotally mounted and disposed beneath the casing, said arm adapted to carry said abutting rod, operating means whereby said arm may be rotated upward to cause abutting contact between the abutting rod and projection to project the signal plate from the casing, and means adapted to automatically withdraw said signal plate into the casing, when said operating means is released.

3. A signal device for automobiles comprising an oscillating arm, a pair of casings mounted thereon, a movable signal plate mounted in each of said casings, a projection on each of the signal plates at the lower edge thereof, a link member at each end of the oscillatory arm in abutment with 95 said projection and adapted to make abutting contact therewith, and means for operating the oscillatory arm.

4. A signaling device for automobiles comprising a pair of casings, each of said casings having an aperture, a movable signal plate mounted in each of said casings, a transparent signal plate mounted in registry with each aperture, the latter plate being uncovered when the movable signal plate is operated, means for illuminating said transparent signal plate when the movable plate is operated, an oscillating arm, a link member at each end of the oscillating arm mounted in operative position relative 105 to the plate and adapted to make abutting engagement therewith, means for operating said oscillating arm adapted to actuate either of said movable signal plates, the other remaining stationary in its case, and 110 a spring attached to the casing and the movable signal plate adapted to retract the actuated signal plate when the operating means are released.

5. A signal device for automobiles comprising indicating members mounted at the front and rear of the vehicle and means for operating the indicating members comprising a shaft running the length of the vehicle, means for rotating said shaft, arms 125

mounted on the shaft and connected with the indicating members, means for illuminating said indicating devices, and a projection on the shaft to close an electric circuit for said illuminating means when the shaft is rotated to operate the indicating member.

Signed at New York city, in the county

of New York, and State of New York, this 23d day of March, A. D. 1915.
